ROTARY HOOK FOR SEWING MACHINES

Walter Myers, Bridgeport, Conn., assignor to The Singer Manufacturing Company, Elizabeth, N. J., a corporation of New Jersey

Original application August 4, 1932, Serial No. 627,409. Divided and this application May 13, 1933, Serial No. 670,910.

7 Claims. (Cl. 112—228)

This invention relates to sewing machines and has for an object to provide an improved rotary hook and bobbin-case mechanism which is cool and clean running under high speed operating 5 conditions.

With the above and other objects in view, as will hereinafter appear, the invention comprises the devices, combinations, and arrangements of parts hereinafter set forth and illustrated in the 10 accompanying drawing of a preferred embodiment of the invention, from which the several features of the invention and the advantages attained thereby will be readily understood by those skilled in the art.

15 In the accompanying drawing, Fig. 1 is a top plan view of the work-supporting arm of a feed-off-arm sewing machine embodying the invention. Fig. 2 is a transverse section through the work-supporting arm. Fig. 3 is a disassembled 20 perspective view of one of the rotary hook and bobbin-case devices shown in Figs. 1 and 2. Fig. 4 is a plan view of the bobbin-case shown in Fig. 3. Fig. 5 is an edge view or elevation of the bobbin-case shown in Figs. 3 and 4, and Fig. 6 25 is a fragmentary sectional view through the bobbin-case bearing rib and hook-raceway.

This application is a division of application Serial No. 627,409; filed Aug. 4, 1932.

1 represents the work-supporting arm of a 30 feed-off-arm sewing machine in which are mounted on pivot screws 2 the laterally adjustable bearing blocks 3 fitted with ball-bearings 4 for the vertical hook-shafts 5, each carrying a cup-shaped rotary hook-body 6 having a portion 35 of its wall cut away to form a loop-seizing beak 7 and a needle-guard 8.

Each hook-body 6 is formed within its rim with a bobbin-case race comprising a vertically cylindrical bobbin-case bearing wall 9 below 40 which is an inwardly extending bearing ledge 10 grooved at 11 adjacent the vertical bearing wall 9 to provide a raised annular horizontal bearing surface 12 spaced inwardly from the vertical bearing wall 9.

45 The bobbin-case 13 has a bearing rib 14 journaled in the hook-race and is formed with a rotation-restraining notch 15 loosely embracing a rotation-restraining lug 16, Fig. 2, on the under side of the throat-plate 17. The bobbin-case is 50 also formed in its loop-cast-on side with a shoulder 18 engaged by the vibratory finger 19 of a bobbin-case opener device to open a passage for the upper limb of the needle-loop, as disclosed in said application Serial No. 627,409. The bobbin-case 13 is retained in the raceway in the

hook-body 6 by means of the flat gib 20 which is screwed to the top of the rim of the hook-body and is formed adjacent the base of the loop-taking hook 7 with a loop-casting hook 21, the point of which terminates in rear of the point 60 of the loop-seizing hook so as to catch one limb of the needle-loop after it is seized by the loop-seizing hook and assist in spreading such loop over the bobbin-case.

For lubrication of the bobbin-case raceway, the 65 bearing rib 14 thereof is made relatively wide vertically and is provided with segmental, closed bottomed, pockets or wells 22 which are filled with felt or similar lubricant-holding wicking. These 70 pockets 22 are formed entirely in the bobbin-case bearing rib 14 and lie wholly below the plane of the under bearing face of the gib 20 and below the upper end of the bobbin-case where they cannot be engaged by the sewing thread to soil the latter. These pockets 22 have a segmental 75 length and vertical depth sufficient to provide a relatively large oil-holding capacity and will efficiently lubricate the respective hook-races for a considerable time without replenishment of lubricant. Laterally extending constricted oil-ducts 80 23 at different levels, Fig. 5, above the bottoms of the pockets 22 feed oil gradually but in sufficient quantity from the pockets to the raceway bearings. By having the constricted ducts 23 at different levels the oil is applied simultaneously 85 to different zones of the vertical bearing walls and more evenly spread thereover without excess.

Having thus set forth the nature of the invention, what I claim herein is:—

1. A rotary hook comprising a cup-shaped 90 hook-body formed within its rim with a cylindrical bobbin-case bearing wall and with an inwardly extending bobbin-case bearing ledge at the base of said wall, the bearing surface of said ledge being grooved adjacent said cylindrical bearing 95 wall to provide an inwardly disposed bearing surface raised above the bottom of said grooved portion and spaced inwardly from said cylindrical wall, and a bobbin-case having a bearing rib engaging said bearing wall and ledge. 100

2. A vertical axis rotary hook comprising a cup-shaped hook-body formed within its rim with a bobbin-case bearing race and cut away in one side wall to form a loop-seizing hook, a stationary 105 bobbin-case journaled in said raceway, and a removable flat circular gib secured to the rim of said hook-body and formed in that portion adjacent the base of the loop-seizing hook with a loop-casting hook the point of which terminates in rear of the point of the loop-seizing hook. 110

3. A sewing machine loop-taker having a race-way, a bobbin-case having a peripheral bearing rib journaled in said raceway, said bearing rib being formed with a closed bottomed oil well and with a relatively constricted lateral oil-duct leading outwardly from one side of said oil-well to the outer bearing surface of said rib.

4. A sewing machine loop-taker having a race-way, a bobbin-case having a peripheral bearing rib journaled in said raceway, said bearing rib being formed with a closed bottomed oil well and with a relatively constricted lateral oil-duct leading outwardly from one side of said oil-well above the bottom of the latter to the outer bearing surface of said rib.

5. A vertical axis rotary hook having a cup-shaped hook-body formed within its rim with a bobbin-case bearing race, a bobbin-case having a bearing rib journaled in said race, said bearing rib having below its upper surface, and within its outer periphery a closed bottomed segmental wick-filled oil-pocket, and a lateral oil-feed duct

leading from said pocket to the outer peripheral bearing surface of said rib.

6. A rotary hook having a cup-shaped hook-body formed within its rim with a bobbin-case bearing race, a gib removably secured to said hook-body and closing the top side of said race, a bobbin-case formed with a peripheral bearing rib journaled in said race, said bobbin-case having below said gib a wick-filled oil-pocket and a constricted lateral oil-duct leading from said oil-pocket to the outer surface of said bearing rib.

7. A sewing machine loop-taker having a race-way, a bobbin-case having a peripheral bearing rib journaled in said raceway, said bearing rib being formed with a plurality of closed bottomed oil-wells and with a plurality of relatively constricted lateral oil-ducts at different levels leading outwardly from said oil-wells above the respective bottoms of the latter to the outer bearing surface of said rib.
